UNITED STATES PATENT OFFICE

ORKNEY P. WILSON AND NOLAN B. ROOKS, OF HUMBOLDT, TENNESSEE; SAID WILSON
ASSIGNOR TO SAID ROOKS

FOLDING PACKAGE

Application filed May 4, 1931. Serial No. 534,960.

The device forming the subject matter of this application is a crate, box, or container, which is an improvement on the article shown in the co-pending application of O. P. Wilson, one of the inventors in the present case, said application having been filed February 3, 1930, and bearing Serial No. 425,614.

The invention aims to provide a combination of parts which will afford a foldable container which can be manufactured as cheaply as a knock-down container, plus the cost of making up the knock-down package, and in a great many instances quite as cheaply as the knock-down package, on account of saving in material, great rigidity resulting, and a general advance in the durability and strength of containers being brought about, without sacrificing the ability of the container to be stowed in small compass, when not in use.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 is a side elevation,

Figure 2 is a top plan,

Figure 3 is a section on the line 3—3 of Figure 2,

Figure 4 is a section on the line 4—4 of Figure 1,

Figure 5 is a plan of the top closure,

Figure 6 is an elevation showing the container folded.

The container preferably is made of wood and is of box-like form. It includes ends 1 and sides 2. Each of the parts 1 and 2 may be made in various ways, but, preferably, each of them comprises bottom bars 3 and top bars 4, connected by slats 5. The

ends 1 are disposed between the sides 2, as shown in Figure 4. Upper metal hinge plates 6 and lower metal hinge plates 11 are disposed respectively on the upper and lower surfaces of the sides 2 and the ends 1, the hinge plates being of approximately rectangular form, and having their outer edges disposed flush with the outer edges of the sides and ends, to form corner protectors, as Figure 2 will clearly show.

Securing elements 7 fix the upper hinge plates 6 to the top bars 4 of the sides 2. Pivot elements 8 pass through the upper hinge plates 6 into the top bars 4 of the ends 1. The top bars 4 of the ends 1 project at 9 beyond the hinge plates 6, a little way, when the container is folded as in Figure 6, so that the ends of the said bars will be disposed close to the corresponding bars of the sides 2, when the container is set up as in Figure 2. The lower hinge plates 11 are mounted as hereinbefore described in connection with the upper hinge plates 6.

A bottom 12, of any desired construction, rests on the inner corners of the lower hinge plates 11. A top 14 is engaged at its left hand end beneath the upper hinge plates 6 at the left hand end of the container in Figure 2. The top 14 is cut away at its right hand end, at its corners, as shown at 15 in Figure 5, to clear the inner corners of the upper right hand hinge plates in Figure 2. A locking strip 17 extends across the right hand end of the top 14 in Figure 2 and is engaged at its ends beneath the right hand upper hinge plates 6 of that figure. All of the hinge plates 6 and 11 have rounded inner corners 10, to prevent catching when the container is handled or moved. The rounding of the inner corners of the right hand hinge plates 6 in Figure 2 enables the top 14 to be cut away at its corners, as shown at 15 in Figure 5, to a minimum, and still the plates 6 will have large areas of contact with the top 14 and with the locking strip 17, the same observation holding true with respect to the lower hinge plates 11 and the bottom 12. Both the top 14 and the bottom 12 fit within the container, and give it rigidity.

The device is simple in construction, and

inexpensive to manufacture. It has all of the advantages of a knock-down crate, and, at the same time, is characterized by great rigidity and strength, not a little of the utility arising out of the specific shape of the hinge plates 6 and 11, and the advantages of the rounded corners 10, as hereinbefore explained.

Having thus described the invention, what is claimed is:

A foldable container comprising sides and ends disposed at right angles to each other, upper and lower hinge plates disposed respectively on the upper and lower surfaces 15 of the sides and the ends, the hinge plates being of approximately rectangular form and having their outer edges disposed substantially flush with the outer edges of the sides and ends, to form corner protectors, 20 pivot elements passing through the hinge plates into the upper and lower edges of the ends, a bottom resting on the inner corners of the lower hinge plates, a top engaged at one end beneath the upper hinge plates at 25 one end of the container, the top being cut away at its corners, at its opposite end, to clear the inner corners of the upper hinge plates at the opposite end of the container, and a locking strip extended across the said 30 opposite end of the top, the locking strip being engaged at its ends beneath the last-specified upper hinge plates, and means for securing the hinge plates fixedly, and against 35 swinging movement, to the sides, said fixed mounting of the hinge plates preventing the ends from moving inwardly, bodily, in a direction transverse to their length, and the approximately rectangular form of the plates preventing relative vertical sagging of the 40 sides and the ends.

In testimony that we claim the foregoing as our own, we have hereto affixed our signatures.

ORKNEY P. WILSON.
NOLAN B. ROOKS.
